HIGH-DENSITY, NONMAGNETIC STAINLESS STEEL

Samuel J. Rosenberg and Thomas P. Royston, Jr., Washington, D.C., assignors to the United States of America as represented by the Secretary of Commerce

No Drawing. Filed Oct. 3, 1961, Ser. No. 142,740

4 Claims. (Cl. 75—128)

This invention relates to a high density, nonmagnetic stainless steel.

By long established custom, the values of weights have been expressed as weight in air against standards having a density of 8.4 grams per cubic centimeter. Weights

5 out in air in a 16 pound laboratory induction furnace and the metal was poured into the form of 1½ inch diameter bars. These were given a four-hour homogenizing anneal in vacuum at 2000° F. prior to hot working. The steels

were hot worked by forging and swaging to rods of about 0.6 inch diameter. Hot working was carried out in the temperature range of about 2100 to 1600° F.

10 After hot working, the rods were cut into lengths of about 6 inches and turned between centers for cleaning. Samples of the clean, hot-worked material were then taken for spectrochemical and chemical analyses and for determination of density and magnetic permeability. The analyses of the two steels that closely approached the desired density are shown in the following table:

Table II

National Bureau of Standards Mark	Percent						
	Carbon	Manganese	Silicon	Chromium	Nickel	Tungsten	Nitrogen
SW-12	0.09	1.7	1.55	16.2	32.4	9.9	0.017
SW-13	0.05	1.7	1.49	16.4	32.4	9.9	0.017

Determination of permeability and density gave the following values:

Table III

National Bureau of Standards Mark	Magnetic Permeability (H=300 Oersteds)			Density, g. per cu. cm.	
	As Hot Worked	As Annealed	As Cold Worked	As Hot Worked	As Annealed
SW-12	1.008	1.019	1.03	8.42	8.44
SW-13	1.009	1.024	1.03	8.45	8.45

that have this density may be compared without a correction for air buoyancy being required.

Brass having a density of 8.4 g. per cu. cm. has been used for many years as material for standard weights. It is nonmagnetic, a necessary property for standards of mass. It is not, however, an ideal material since it tarnishes and thus is subject to changes in weight.

Accordingly, it is an object of the present invention to provide a stainless steel that has the required density and is nonmagnetic.

This is accomplished by increasing the density of an austenitic stainless steel by the addition of tungsten and maintaining austenite stability by proper balance of chromium and nickel. The preferred percent of elements and the range or maximum percent of elements, besides iron and the usual impurities, used in the present invention are indicated in the following composition table:

Table I

	Composition, percent	
	Preferred	Range or Maximum
Carbon	0.10	0.20 max.
Manganese	1.70	2.00 max.
Phosphorus		0.040 max.
Sulfur		0.030 max.
Silicon	1.25	1.60 max.
Chromium	16.5	15.5 to 17.5.
Nickel	32.5	31.5 to 33.5.
Tungsten	9.5	9.0 to 10.0.

In the execution of this invention, several experimental steels were melted and fabricated. Melting was carried

40 It is noted that an increase in magnetic permeability was obtained after annealing the hot-worked material. The remanent induction of the hot-worked specimens was measured after they had been subjected to magnetizing forces of several thousand oersteds. The measured remanent induction was negligible in comparison with the earth's field.

45 It is understood that while laboratory techniques were used in preparing the above alloys, which were given by way of example, other conventional furnace procedures may be followed in using the present invention.

50 What is claimed is:

1. A high density, nonmagnetic steel, of approximately 8.4 grams/cm.³ and consisting essentially of:

55 carbon ..... 0.20% maximum
manganese ..... 2.00% maximum
phosphorous ..... 0.040% maximum
sulfur ..... 0.030% maximum
silicon ..... 1.60% maximum
chromium ..... 15.5 to 17.5%
nickel ..... 31.5 to 33.5%
60 tungsten ..... 9.0 to 10.0%
and the balance of said steel being essentially iron.

65 2. A high density, nonmagnetic steel of approximately 8.4 grams/cm.³ and consisting essentially of:

65 carbon 0.10%
manganese 1.70%
silicon 1.25%
chromium 16.5%
nickel 32.5%
70 tungsten 9.5%
and the balance of said steel being essentially iron.

3. A high density, nonmagnetic steel of approximately 8.4 grams/cm.³ and consisting essentially of:

carbon	0.09%
manganese	1.7%
silicon	1.55%
chromium	16.2%
nickel	32.4%
tungsten	9.9%
nitrogen	0.017%

and the balance of said steel being essentially iron.

4. A high density, nonmagnetic steel of approximately 8.4 grams/cm.³ and consisting essentially of:

carbon	0.05%
manganese	1.7%
silicon	1.49%
chromium	16.4%
nickel	32.3%

tungsten	9.9%
nitrogen	0.017%

and the balance of said steel being essentially iron.
